DESIGN FOR A LIGHTING FIXTURE

Frank F. Holstein, Chicago, Ill.

Application November 8, 1935, Serial No. 59,450

Term of patent 7 years

To all whom it may concern:

Be it known that I, Frank F. Holstein, a citizen of the United States, residing at Chicago, Cook County, Illinois, have invented a new, original, and ornamental Design for a Lighting Fixture, of which the following is a specification, reference being had to the accompanying drawing, forming a part thereof.

Figure 1 is a front elevational view of the lighting fixture showing my new design.

Figure 2 is a side elevational view.

Figure 3 is a cross-sectional view thereof. The dominant feature of my design resides in the location of the mask element a distance in front of the reflector member, with a light bulb interposed therebetween which supplies a band of light around the outer periphery of the masked portion.

I claim:

The ornamental design for a lighting fixture as shown and described.

FRANK F. HOLSTEIN.
